E. C. Ford
By his Atty
R. D. Smith

UNITED STATES PATENT OFFICE.

EDWARD C. FORD, OF LAUREL, MARYLAND.

HANGER FOR PLUMBERS' PIPES.

SPECIFICATION forming part of Letters Patent No. 258,638, dated May 30, 1882.

Application filed April 4, 1882. (No model.)

To all whom it may concern:

Be it known that I, EDWARD C. FORD, of Laurel, Prince George's county, Maryland, have invented a new and useful Hanger-
5 Bracket for the Support of Water and Gas Pipes below the Ceiling of an Apartment; and I do hereby declare that the following is a full and exact description of the same.

Until recently it was customary to con-
10 ceal the water-pipes under the floors or in the walls to the greatest extent possible, and when not concealed they were fastened against the ceiling or wall. The modern practice is to leave such pipes exposed and accessible to
15 the greatest possible extent; and by this invention I propose to provide means for the suspension of such pipes clear of the wall or ceiling, whereby the pipes are not only ren-
dered freely accessible for repairs, but may
20 be easily and thoroughly cleaned, and no longer become resting-places for dust or harbor for vermin.

That others may fully understand my in-
vention, I will more particularly describe it,
25 reference being had to the accompanying
drawings, wherein—

Figure 1 is a perspective view of my brack-
et. Fig. 2 is a side elevation of the same,
showing also a lateral adjustment of the ex-
30 terior hooks. Fig. 3 is a vertical section of
the same. Fig. 4 is a side elevation, which
merely illustrates the variety of design which
may be employed without departing from the
invention.

35 I have been informed that plumbers usu-
ally group three pipes, and for that reason I
represent a bracket provided with saddles for
three pipes. The number can be increased or
diminished, however, and the bracket provid-
40 ed with any number desired.

A is a plate which is attached to the wall
or ceiling, and a common mode of attach-
ment is shown in Fig. 2, where B B repre-
45 sent the lath, and C the plastering. The po-
sition and direction of the pipes D is fixed
without reference to the places of attachment
for the bracket-screws e, and it will often be
found necessary to pass these into laths B,
there being no joists or studs available. I

therefore provide a plate, A, with two slots, f 50
f, and the screw e may be placed in one part
or another of its slot, as may be necessary to
reach the center of a lath, and thus obtain a
good support.

From the plate A one or more arms, F, de-
55 scend. I prefer to employ two of said arms, as
shown in Figs. 1 and 2.

A horizontal part, G, provided with the
saddles h h h, is also provided with arms cor-
60 responding with and fitted to the arms F, so
that they may be secured together by adjust-
ing-screws i i, or some equivalent device, so
that the saddles h may be raised or lowered.
This is desirable, because in suspending these
65 pipes below the ceiling, it is desirable to place
the pipes lower at one end than at the other,
so as to secure drainage. The vertical ad-
justment is shown by dotted lines in Fig. 3.

It will also be necessary sometimes to vary
the horizontal distances between the pipes,
70 and therefore a horizontal adjustment will
also be useful. This is shown in Figs. 2 and 4,
where the outer saddles, h, are movable hori-
zontally, so as to place the pipes nearer or far-
ther apart.

75 The pendent portions k of the part G is
simply for ornament and to enable the plumber
to place his name, if he desires. This part may
be entirely omitted, if preferred.

The structure shown in Fig. 4 may be built
80 up of plumbers' T-couplings, &c., but may be
more cheaply and just as efficiently cast solid
in imitation of plumbers' work; or such other
design may be employed as fancy or conven-
ience may dictate.

Having described my invention, what I claim
as new is—

1. A hanger or bracket for plumbers' use,
85 consisting of a plate, A, with means for at-
tachment to the ceiling, combined with a part,
G, and saddles h, horizontally adjustable, sub-
stantially as set forth.

2. A hanger or bracket for plumbers' use,
90 consisting of a part, A, for attachment to the
wall, and a part, G, provided with saddles h,
95 combined with slots f in the part A, whereby
the fastening-screws e may have a lateral
range of location irrespective of the location

of the bracket, as and for the purpose set forth.

3. A hanger or bracket for plumbers' use, consisting of a plate, A, provided with means for attachment to the ceiling having a range of lateral location irrespective of the location of the bracket, combined with a part, G, and

saddles h h , which are capable of vertical and horizontal adjustment, substantially as set forth.

EDWARD C. FORD.
